US00D844466S

(12) **United States Design Patent** (10) Patent No.: **US D844,466 S**
 Shaughnessy (45) Date of Patent: ** Apr. 2, 2019

(54) **TEMPERATURE SENSOR**

(71) Applicant: **Unison Industries, LLC**, Jacksonville, FL (US)
 (72) Inventor: **Kyle Shaughnessy**, Vernon, CT (US)
 (73) Assignee: **Unison Industries, LLC**, Jacksonville, FL (US)

(**) Term: **15 Years**

(21) Appl. No.: **29/608,548**

(22) Filed: **Jun. 22, 2017**

(51) LOC (11) Cl. **10-04**

(52) U.S. Cl.

USPC **D10/53**

(58) **Field of Classification Search**

USPC D10/57, 52, 53, 55, 56, 60

CPC G01F 1/661; G01F 15/046

FOREIGN PATENT DOCUMENTS

CA 2449335 1/2008

Primary Examiner — Antoine Duval Davis

(74) Attorney, Agent, or Firm — Unison Industries, LLC; Pamela Kachur

(57) **CLAIM**

The ornamental design for a temperature sensor, as shown and described.

DESCRIPTION

FIG. 1 is a top, rear perspective view of a temperature sensor;

FIG. 2 is a top, front perspective view of the temperature sensor of FIG. 1;

FIG. 3 is a top view of the temperature sensor of FIG. 1; FIG. 4 is a front side view of the temperature sensor of FIG. 1;

FIG. 5 is a rear side view of the temperature sensor of FIG. 1;

FIG. 6 is a right side view of the temperature sensor of FIG. 1;

FIG. 7 is a left side view of the temperature sensor of FIG. 1; and,

FIG. 8 is a cross-sectional view of the temperature sensor of FIG. 7 taken along the line 8-8.

Portions of the temperature sensor shown in broken line form no part of the claimed design.

1 Claim, 8 Drawing Sheets
